UNITED STATES PATENT OFFICE.

TAYLOR J. SMITH, OF UNION CITY, GEORGIA, ASSIGNOR OF ONE-HALF TO SAMUEL M. COWN, OF UNION CITY, GEORGIA.

GEARING.

1,140,078.

Specification of Letters Patent. Patented May 18, 1915.

Application filed December 8, 1913. Serial No. 805,207.

To all whom it may concern:

Be it known that I, TAYLOR J. SMITH, a citizen of the United States, residing at Union City, in the county of Campbell and 5 State of Georgia, have invented certain new and useful Improvements in Gearing, of which the following is a specification.

My invention relates to improvements in gearing especially adapted for use with 10 churning, the object of the invention being to provide an improved arrangement of triple dasher shafts with an improved mounting therefor enabling the mechanism to be readily placed within and removed from a suitable container, and which protects the working 15 parts of the churn against possibility of contact with the cream, and thereby prevents injurious consequences to the cream as well as to the working parts.

20 A further object is to provide improvements of this character in which the upper ends of the dasher shafts and the gearing imparting motion thereto is confined within a housing located centrally of a plate, which 25 latter is designed to cover a container and permit of ready removal when desired.

With these and other objects in view, the invention consists in certain novel features of construction and combinations and arrangements of parts as will be more fully 30 hereinafter described and pointed out in the claim.

In the accompanying drawings: Figure 1 is a view in vertical section illustrating my 35 improvements. Fig. 2 is a top plan view. Fig. 3 is a fragmentary view in section on the line 3—3 of Fig. 1. Fig. 4 is a view in horizontal section on the line 4—4 of Fig. 1. Fig. 5 is a view in section on the line 40 5—5 of Fig. 1. Fig. 6 is a perspective view of one of the dashers.

1 represents a container which may be of any suitable material having at a point below its open upper end, an internal annular 45 flange 2 with notches 3 formed therein.

4 represents a plate which is of general conical form and of a diameter to fit within the container 1, and rest upon the flange 2 of the latter. A depending annular flange 50 5 is formed on plate 2 at a point removed from its outer edge, and this flange 5 projects into the receptacle within the flange 2, and is provided with lugs 6 which are adapted to be projected through the notches 3,

and when the plate is turned, securely lock 55 the plate in the container.

The plate 4 is provided centrally with a pocket 7 over which a removable casting 8 is secured by means of screws 9, which latter extend through the lower end of the casting 8, and are screwed into the plate 4. The casting 8 and the pocket 7 together constitute a gear housing in which my improved arrangement of gearing is inclosed.

Plate 4 in the bottom of housing 7, is 65 formed with integral bearings 10 through which dasher shafts 11 project. The upper ends of these shafts 11, which are reduced in diameter as shown at 12, project into bearings 13 in enlargements 14 integral with 70 casting 8, so that the shafts have two bearing points at their upper ends, one in the plate 4, and the other in the casting 8. I have illustrated, and preferably employ three dasher shafts which at their lower reduced ends are supported to turn in bearings 15 in a ring 16. This ring is held in position by nuts 17 on the lower screw-threaded ends of the shafts 11 below the ring as indicated clearly in Fig. 1. 80

Each shaft 11 is provided with dashers 18 having central sleeves 19 secured to the dasher shafts in any desired manner and projecting at both ends beyond the shaft, and preferably perforated as shown at 20. 85 My invention is not limited to any particular number of these dashers, but they have staggered arrangement, so that when the shafts revolve, the dashers of one shaft may move between the dashers of another. 90

In the center of pocket 7, a short arbor 21 is secured and supports a gear 22 which meshes with pinions 23 on each of the dasher shafts 11, and transmits motion to all of the shafts to turn them simultaneously. 95

An integral beveled pinion 24 is formed on gear 22, and meshes with a beveled driving gear 25 secured on a horizontal shaft 26 projecting beyond the casting 8 and having a crank arm 27 thereon to turn the same. 100

While my invention is not limited to any particular style of container, it is especially adapted for use on earthenware jars or similar receptacles, and the construction of plate 4 with its lugs 6 is especially adapted for 105 interlocking in a container of this kind.

It will be noted that when the shaft 26 is turned, gear 25 will impart motion to pinion

24 and gear 22 to drive all of the dasher shafts 11 through the medium of the pinions 23, and cause the dashers to move rapidly through the cream and quickly churn 5 the same into butter.

The shafts, as above stated, have two bearings at their upper ends, one in the plate 4, and the other in the casting 8 with the pinions 23 secured on these shafts between these 10 two bearing points, so that the pinions are firmly held in mesh with the center gear 22 and a strong properly meshing gearing is had. Furthermore, all of the operating parts are safely housed within the housing 15 formed by casting 8 and pocket 7, so that none of the cream can get into the gearing and no grease or dirt from the gearing can find its way into the cream. The device is therefore a perfectly sanitary one, and all 20 of the operating parts are in a strong assemblage which may be readily placed in a container and thoroughly cleansed after the churning operation.

Various slight changes might be made in 25 the general form and arrangement of parts described without departing from my invention, and hence I do not limit myself to the precise details set forth, but consider myself at liberty to make such changes and al-

terations as fairly fall within the spirit and 30 scope of the appended claim.

Having thus described my invention, what I claim as new and desire to secure by Letters Patent is:

A housing comprising a plate provided 35 with a pocket in its upper face, and a super-imposed member detachably secured thereto, an arbor projecting upwardly from the bottom of said pocket, a gear wheel rotatably mounted on said arbor and arranged within 40 said pocket, said gear wheel being provided with an integral beveled pinion, a transverse shaft in said super-imposed member, a beveled gear fixed to said shaft and meshing with said beveled pinion, alined bearings in 45 said plate and super-imposed member respectively, a shaft mounted in said bearings, and a pinion on said shaft within said pocket and meshing with the first said gear, substantially as described. 50

In testimony whereof I have signed my name to this specification in the presence of two subscribing witnesses.

TAYLOR J. SMITH.
